UNITED STATES PATENT OFFICE.

PETER H. KELLY, OF CLINTON, IOWA, ASSIGNOR, BY DIRECT AND MESNE ASSIGNMENTS, TO LOVELL MANUFACTURING COMPANY, OF ERIE, PENNSYLVANIA, A CORPORATION OF PENNSYLVANIA.

CLOTHES-WRINGER.

1,100,830.

Specification of Letters Patent. Patented June 23, 1914.

Application filed January 16, 1913. Serial No. 742,354.

To all whom it may concern:

Be it known that I, PETER H. KELLY, a citizen of the United States, residing at Clinton, in the county of Clinton and State 5 of Iowa, have invented a new and useful Improvement in Clothes-Wringers, of which the following is a specification.

My invention relates, particularly, to an improvement in means for effecting quickly 10 the release of the movable clamping roll from the companion roll in a clothes wringer or mangle, in the event of accident, such as the hand of the operator or laundry-work becoming caught between the rolls.

15 In the accompanying drawings, Figure 1 is a view in front elevation of a clothes-wringer equipped with my invention; Fig. 2 is an end view of the same; Fig. 3 is a broken section on line 3, Fig. 2; Fig. 4 is a 20 section on line 4, Fig. 3; Fig. 5 is an enlarged perspective view showing one of the two similar latch and set-screw carrying yokes or saddles and catch-stud devices provided on the top of the wringer at its opposite 25 site ends. Fig. 6 is a perspective view of the channel pieces carrying the catch studs; Fig. 7 is a perspective view of the latches having the releasing handle.

The general construction of the wringer 30 illustrated for showing my invention is one in common use: Upright side-stiles 6, 6 contain vertical slots, as shown of the slot 7 in Fig. 2, extending from the upper ends of the stiles and provided in their lower ends with 35 bearings for the drive-shaft 8 of the lower roll 9. The upper roll 10 and lower roll are journaled to work in metal heads 11, 11, at the inner sides of the side-stiles, the upper roll being vertically movable in its bearings 40 relative to the roll 9 for the co-operation of the rolls in feeding the work between them, the pressure against the roll 10 being exerted at its journal-ends through the medium of adequately-stiff spiral springs 12 45 each confined between a cap 13 straddling a journal and a tongue 14 projecting over the top of the respective spring from the adjacent end of a cross-bar 15 which rests at the tongues 14 upon the opposite springs 12. 50 The side-stiles 6 are fastened together at their upper ends by a top-rail 16 let, at its end-portions, into the upper ends of the slots 7 and rigidly fastened therein. A pair of metal channel-pieces 17 embraces trans-

versely each stile 6 near its upper end to 55 reinforce it and each piece 17 has a catch-stud 18 projecting from one face, the channel-piece being bolted in place through the stile, as shown at 19, and the members of each pair thereof being shown to be further secured in place by a bolt 20 passing through them and transversely through the top-rail 16 to secure the latter. On the upper end of each stile 6 is loosely seated a saddle 21 provided centrally between its 60 ends with an internally-threaded nut-forming sleeve 22 for a set-screw 23 to adapt the latter to bear and work at its inner end against a tongue 14. To the sides of the saddles are pivoted latches 24 to engage with 65 the catch-studs 18 for releasably locking the saddles in place, whereby, when the set-screws are turned in the proper direction, they force the tongues 14 against the springs 12 to compress them and thus tighten the 70 roll 10 against its companion-roll, and when the catches are disengaged from the studs, the saddles are released, and with them the nuts 22 and set-screws are withdrawn to free the springs 12, permitting them to recoil and 75 thus remove the pressure against the roll 10. To enable the latches to be all worked together, for engaging them with and disengaging them from the studs 18, they are 80 connected in pairs by rods 25; and the pair 85 of latches on one stile 6 are extended outwardly, at their lower ends, as tongues 24¹, which are connected by a handle 26 for manipulating the latches at one end of the wringer. 90

I realize that considerable variation is possible in the details of construction of my present improvement thus specifically shown and described, and I do not intend by illustrating a single, specific, or preferred form, 95 to limit my invention thereto; my intention being in the following claims to claim protection upon all the novelty there may be in the device as broadly as the state of the art will permit. 100

What I claim as new and desire to secure by Letters Patent, is:—

1. In a clothes wringer, the combination of a presser roll; a frame in which the presser roll is mounted comprising side stiles 105 and a top bar rigidly secured to the side stiles; a spring arranged at each end of the presser roll and between the presser roll and

top bar; a screw for adjusting each spring; a nut for each screw slidingly mounted in the top bar; and means for locking said nuts in the top bar; and connected devices for instantaneously releasing both means to release the nuts and the pressure on the roll.

2. In a clothes wringer, the combination with an adjustable roll of the device and springs confined against its ends, of saddles 5 on the upper ends of the frame-stiles and provided with internally-threaded sleeves, set-screws working in said sleeves against

the springs to set said roll relative to the companion-roll, pivotal latches depending in pairs from the ends of the saddles, one 15 pair of said latches having a handle, rods connecting corresponding members of the latch-pairs, and catch-studs on said stiles releasably engageable by said latches.

PETER H. KELLY.
